(57) **CLAIM**

I claim the ornamental design for a scalloped cap, as shown and described.

DESCRIPTION

FIG. 1. is a perspective view of a first embodiment of the scalloped cap showing my new design;

FIG. 2. is a first side elevational view thereof;

FIG. 3. is a second side elevational view thereof;

FIG. 4. is a third side elevational view thereof;

FIG. 5. is a fourth side elevational view thereof;

FIG. 6. is a top plan view thereof;

FIG. 7. is a bottom plan view thereof;

FIG. 8. is a perspective view of a second embodiment of the scalloped cap;

FIG. 9. is a first side elevational view thereof;

FIG. 10. is a second side elevational view thereof;

FIG. 11. is a third side elevational view thereof;

FIG. 12. is a fourth side elevational view thereof;

FIG. 13. is a top plan view thereof; and,

FIG. 14. is a bottom plan view thereof.
